CLAIM

The ornamental design for a heating pad, as shown and described.

DESCRIPTION

FIG. 1 is an upper front perspective view of a heating pad of which the lower rear perspective view is a mirror image. FIG. 2 is a top view of the heating pad as shown in FIG. 1, of which the bottom view is a mirror image.

FIG. 3 is a front view of the heating pad as shown in FIG. 1, of which the rear view is a mirror image; and,

FIG. 4 is a left view of the heating pad as shown in FIG. 1, of which the right view is a mirror image.

The broken lines depict portions of the heating pad that form no part of the claimed design.

1 Claim, 4 Drawing Sheets
